UNITED STATES PATENT OFFICE

NAPOLEON B. DOUGLASS, OF BERKELEY, CALIFORNIA, ASSIGNOR TO THE ROME COMPANY, INC., OF ROME, NEW YORK, A CORPORATION OF NEW YORK

WALL BED

Application filed April 15, 1929. Serial No. 355,017.

My present invention relates to wall beds and mountings, and more particularly to pivoted beds adapted to swing into and out of closets through an opening in the wall narrower than the width of the bed.

One of the objects of this invention is to provide a pivotal hanger for folding beds whereby they may be swung into and out of closets and have a movement substantially tangential to the arc of the swinging movement, whereby considerable clearance will be provided between the bed and the door frame in its swing.

Another object of this invention is to support the bed in its evolution so that it may swing into a shallow closet through a narrow door opening and leave a free passage through the opening when the bed is in its operative and inoperative positions.

Other objects and advantages will appear as the description proceeds.

I shall outline in full that form of the invention selected for illustration in the drawings accompanying and forming a part of the present specification. The novelty of the invention will be included in the claims following said description. From this, it will be apparent that I do not restrict myself to the showing made by said drawings and description, as I may adopt many variations within the scope of my invention as expressed in said claims.

In the drawings—

Fig. 1 is a perspective view showing my improved bed and mounting with the supporting wall outlined by dot and dash lines, and

Figs. 2, 3, 4, and 5 are plan views, partially in section, showing the bed in the several different positions which it assumes in swinging from its concealed to its exposed positions.

Referring now to Fig. 1, 10 designates the head frame of a folding bed which may be of any suitable type, but preferably one of the type of which the bed portion 11 is adapted to be swung upwardly into a vertical position. The frame 10 is provided with a pair of horizontally extending and parallel spaced rails 12 and 13. These rails, in the present in-

stance, are illustrated as formed along the horizontal sides of a rectangular frame of channel-shaped cross section. Arranged between the rails 12 and 13, there is shown a carriage 14 having grooved wheels 15 and 16 arranged respectively along its top and bottom sides so that when the whole is assembled, the frame formed by the rails 12 and 13 may ride horizontally with respect to the carriage 14. Extending outwardly from the carriage 14 there are shown suitable supporting arms 17 and 18. These supporting arms 17 and 18 engage suitable pivotal supports 19 and 20 mounted upon the frame of the doorway through which the bed is to swing. The frame in this figure of the drawings is, as previously stated, outlined by dot and dash lines and is designated by the numeral 21.

With the arrangement above described, it will be readily seen that the bed will have two distinct ranges of movement, one being horizontal or sidewise with respect to the carriage 14; and the other being in a circle about the pivot points 19 and 20. It will also be seen that the effect of the combination of these two movements when carried out simultaneously will be to permit a movement of the bed which will not necessarily be circular and, in fact, it is contemplated that this movement will carry the plane of the bed so that its movement will be tangential to the arc of a circle described about the above referred to pivot points.

In order to effect a movement of the bed which will combine both its sidewise movement and pivotal movement and also maintain the bed closely adjacent the edge of the opening upon which it is supported, I provide a link 22, the link being connected between a point 23 upon the bed and a pivotal connection 24 located within the bed enclosing compartment.

By referring now to Figs. 2, 3, 4, and 5, it will be seen that when the bed 11 is in its concealed position the door opening may be closed by a door of standard construction, the door in these figures of the drawings being designated by the numeral 25. In this illustration it will also be noted that the link 22 has assumed such a position that it has caused the

bed to move over on the carriage 14 to such a position that a passageway is provided through the opening and about the side of the bed. As the bed is swung around, as illustrated in Figs. 3 and 4, the link will continue to function and control the position of the bed upon the carriage 14 so that it will pass freely through the opening and at the same time prevent the bed running wild upon its support and thus accidentally interfering with its free passage through the doorway.

In Fig. 5 the bed is shown in its final and operative position.

From the above it will be evident that I have provided a new and novel type of wall bed mounting which is relatively simple and cheap to manufacture and one which will support a full-sized bed so that it can be moved in and out through a door opening substantially narrower than the width of the bed and one which will provide a passageway for the operator through the opening when the bed is in both its exposed and concealed positions.

Having thus described my invention, what I claim and desire to secure by Letters Patent is—

1. For combination with a wall having an opening, a wall bed of greater width than said opening, a bed supporting carriage pivotally mounted at one jamb of said opening and adapted to swing in a horizontal plane, means carried by said bed adapted to engage said carriage and permit the bed to ride sideways thereupon as the carriage is pivoted about its support, and means automatically to cause the bed to ride sideways on said carriage as the carriage is pivoted about its support.

2. For combination with a wall having an opening, a wall bed of greater width than said opening, a bed supporting carriage pivotally mounted adjacent one jamb of said opening and adapted to swing in a horizontal plane, means carried by said bed and engaging the carriage for sidewise movement thereon, and a link secured between the bed and a fixed point adjacent the pivotal point of said supporting carriage for limiting the sidewise movement of the bed as the support swings upon its pivot.

3. For combination with a wall having an opening, a wall bed of greater width than said opening, a support for said bed comprising a vertically disposed carriage pivotally mounted upon one of the jambs of said opening and adapted to swing in a horizontal plane, anti-friction rollers upon said carriage, rails secured to said bed and adapted to engage said anti-friction means whereby the bed may ride freely in a sidewise direction upon said carriage, and a link connected between a fixed point and said bed adapted to impart a side-

wise movement of the bed upon the carriage as the latter swings about its pivot.

4. For combination with a wall having an opening, a wall bed of greater width than said opening, a carriage supporting said bed and pivotally mounted at one jamb of said opening, the axis of said pivotal mounting being outside the plane of the bed, horizontally disposed rails secured to said bed and adapted to engage said carriage and support the bed so that it can ride sideways upon the carriage, and means pivotally secured to the bed and to a fixed point to guide the movement of the bed through the opening.

5. For combination with a wall having an opening, a wall bed of greater width than said opening, a carriage supporting said bed and pivotally mounted at one jamb of said opening, the axis of said pivotal mounting being outside the plane of the bed, horizontally disposed rails secured to said bed and adapted to engage said carriage and support the bed so that it can ride sideways upon the carriage, and a link pivotally secured to the bed and to a fixed point outside the axis of rotation of said carriage.

6. For combination with a wall having an opening, a wall bed of greater width than said opening, a carriage supporting said bed and pivotally mounted at one jamb of said opening, the axis of said pivotal mounting being outside the plane of the bed, horizontally disposed rails secured to said bed and adapted to engage said carriage and support the bed so that it can ride sideways upon the carriage, and a link pivotally secured to the bed and to a fixed point outside the axis of rotation of said carriage, the length of said link being greater than the shortest distance between said carriage and its pivot point.

7. For combination with a wall having an opening, a wall bed of greater width than said opening, a carriage supporting said bed and pivotally mounted at one jamb of said opening, the axis of said pivotal mounting being outside the plane of the bed, horizontally disposed rails secured to said bed and adapted to engage said carriage and support the bed so that it can ride sideways upon the carriage, and a link pivotally secured to the bed and to a fixed point on the floor behind said jamb.

8. For combination with a wall having an opening, a wall bed of greater width than said opening, a carriage supporting said bed and pivotally mounted at one jamb of said opening, the axis of said pivotal mounting being outside the plane of the bed, horizontally disposed rails secured to said bed and adapted to engage said carriage and support the bed so that it can ride sideways upon the carriage, and a bent link pivotally connected to said bed and to a fixed point on the floor behind said jamb.
